(57) **CLAIM**

The ornamental design for a metal wood sole having composite wedges, as shown and described.

DESCRIPTION

FIG. 1 is a bottom perspective view of the metal wood sole having composite wedges of the present invention.

FIG. 2 is a perspective view of the metal wood sole having composite wedges from the toe side thereof.

FIG. 3 is a perspective view of the metal wood sole having composite wedges from the heel side thereof.

FIG. 4 is a bottom plan view of the metal wood sole having composite wedges thereof.

FIG. 5 is a toe view of the metal wood sole having composite wedges thereof.

FIG. 6 is a top plan view of thereof; and,

FIG. 7 is a front view thereof.

The broken line showing is for illustrative purposes only and forms no part of the claimed design.
